MERINGUE PIE

Monroe Boston Strause, San Diego, Calif.

Application April 15, 1949, Serial No. 1,992

Term of patent 14 years

(Cl. D8—1)

To all whom it may concern:

Be it known that I, Monroe Boston Strause, a citizen of the United States of America and residing at San Diego, county of San Diego, State of California, have invented a new, original, and ornamental Design for a Meringue Pie, of which the following is a specification, reference being made to the accompanying drawings, forming part thereof.

Fig. 1 is a perspective view of a meringue pie, showing my new design, and

Fig. 2 is a top plan view thereof.

The sides of the slots and portions of the top are toast colored golden brown.

I claim:

The ornamental design for a meringue pie, substantially as shown and described.

MONROE BOSTON STRAUSE.
